APPARATUS FOR MANUFACTURING
RADIATORS

Stanley D. Payzer, Everett A. Preston, and Carl E. Staky, Wausau, Wis., assignors to D. J. Murray Manufacturing Co., Wausau, Wis., a corporation of Wisconsin

Application August 7, 1933, Serial No. 683,942

7 Claims. (Cl. 22—131)

The present invention relates in general to improvements in the art of manufacturing radiators and similar structures having a plurality of relatively thin and closely adjacent fins constituting a part thereof, and relates more specifically to improved apparatus for producing such structures by casting the same en bloc.

It has heretofore been proposed to produce finned radiator structures by casting the same with the aid of a plurality of adjoining flat fin cores each provided with upper and lower lateral projections adapted to engage an adjacent core so as to produce a fin space, the entire assemblage of cores being confined within a horizontally divided green sand mold prior to the casting operation. While this prior method of casting these radiator structures, insures the production of relatively satisfactory castings, the spacing projections at the lower ends of the fin cores are not desirable or necessary, and the use of an enveloping green sand mold is also unnecessary and merely adds to the cost of production of the radiator castings.

The present invention therefore contemplates and has for an object the provision of improved instrumentalities for constructing radiators or radiator sections of the finned type, of any desired length, with the aid of cores alone and without the use of green sand or other enveloping molds for the cores.

Another object of the present invention is to provide an improved core assemblage for facilitating the casting of radiators or radiator sections of various lengths having integral cast fins completely surrounding relatively larger fluid conducting conduits extending transversely of the fins and longitudinally of the radiators and interconnecting the end headers thereof.

Still another object of the invention is to provide improved apparatus for producing successive perfect cast structures having a multiplicity of integral thin and closely adjacent spaced walls such as fins, rapidly and with minimum waste of time and material resulting from defective castings.

These and other objects and advantages will be apparent from the following detailed description.

A clear conception of several embodiments of apparatus adapted to carry on the commercial exploitation of the present mode of casting finned radiator sections, may be had by referring to the drawings accompanying and forming a part of this specification in which like reference characters designate the same or similar parts in the various views.

Fig. 1 is a part sectional top view of one type of

core mold for casting an elongated radiator section provided with a multiplicity of radiating fins with spaces therebetween;

Fig. 2 is a transverse vertical section through the core mold of Fig. 1, taken along the line 2—2;

Fig. 3 is an elevation of one of the end cores constituting the mold of Fig. 1, the view being taken at the line 3—3 of Fig. 1;

Fig. 4 is another transverse vertical section through the radiator mold of Fig. 1, taken along the line 4—4;

Fig. 5 is an additional transverse vertical section through the radiator mold of Fig. 1, taken centrally thereof along the line 5—5;

Fig. 6 is a longitudinal vertical section through a fragment of the mold assemblage of Fig. 1, taken along the line 6—6;

Fig. 7 is a central longitudinal vertical section through a similar fragment of the mold of Fig. 1, taken along the line 7—7;

Fig. 8 is a full top view of a cast radiator section produced with a mold such as shown in Fig. 1;

Fig. 9 is a transverse section through the radiator structure of Fig. 8, taken along the line 9—9;

Fig. 10 is a longitudinal section through the radiator structure of Fig. 8, taken along the irregular line 10—10; and

Fig. 11 is an enlarged central longitudinal section through a modified type of composite radiator mold.

While the invention has been shown and described herein as being specifically applied in conjunction with the casting of a particular type of sectional finned radiators, it is not intended to limit the scope by such specific disclosure, and some of the novel features may obviously be more generally applicable to the casting of other kinds of finned objects.

Referring specifically to Figs. 1 to 7 inclusive, the improved mold utilized in casting radiator sections, comprises in general a base of slab core formed of interlocking base portions 14, 15; a pair of spaced radiator end chamber cores 16 resting upon and projecting into recesses in the main base portion 14 and inter-connected by one or more parallel radiator conduit cores 17; and a plurality of flat rectangular end and fin cores locked to the slab core and coacting with each other and with the chamber and conduit cores 16, 17 to complete the mold structure.

The portions 14, 15 of the base core having a longitudinally interlocking tongue and groove joint 18 and may be of any desired length depend-

ing upon the length of the radiator sections which are to be cast, and the base core may be confined within a suitable retainer box 19 having tapered side walls cooperable with similarly tapered side surfaces 20 of the core portions 14, 15, to hold these portions snugly together. The base core portions 14, 15 are also provided with longitudinally extending tapered grooves at the opposite sides of the upper surface of the slab, 10 which are adapted to coact with lower projections 21 formed on the opposite sides of the flat end and fin cores, in order to firmly hold these upper cores in assembled position. The main portion 14 of the base core is moreover provided with a center gate 22 which communicates with passages 15 23 leading upwardly through the central portion of the upper supporting face of this core, as clearly shown in Fig. 5.

The radiator manifold or end chamber cores 16 20 are provided with upper and lower core prints 24, 25, of which the lower prints 25 rest upon and project into a recess in the upper face of the slab core portion 14 and thus provide supports for the cores 16, while the upper prints 24 coact with and 25 project through a hole in the upper portions of the end fin cores. The radiator conduit cores 17 may be one or more in number, and have their 30 end portions 26 inserted in side recesses of the manifold cores 16 as shown in Fig. 6, being thereby supported parallel to each other and in vertically spaced relation with respect to the upper surface of the slab core portion 14.

Disposed at each end of the mold and beyond the adjacent manifold core 16, is a series of three 35 adjoining relatively thick rectangular cores 27, 28, 29. The extreme end cores 27 are merely flat slabs having locking projections 21 at the opposite lower side portions thereof, engageable with the tapered locking grooves of the supporting core 40 portions 14, 15. The outer end faces of the end cores 27 are adapted to be engaged by clamping devices 30 of any desired construction, coacting with the base core confining box 19, and the upper and side portions of the opposite face of one 45 of the cores 27 is provided with lateral projections 31 adapted to interlock with a groove in the adjoining end gate core 28. These end gate cores 28 are shown in Fig. 2, being provided with lateral passages 32 and with other smaller passages 50 33, 34 which register horizontally with similar openings extending through intervening cores throughout the length of the mold. The innermost thick cores 29 of the end series, are merely 55 provided with through openings or passages 33, 34 as shown in Fig. 3, and all of the cores disposed between the outer end cores 27 are interlocked with the adjoining cores and with the supporting slab core portions 14, 15, by means of projections 31, 21 in the manner previously described. 60 The thick end cores 27, 28, 29 are all supported directly upon the upper horizontal surface of the slab core portion 14, and snugly engage each other as well as the portions 14, 15.

Coacting with the innermost thick rectangular 65 cores 29, are thin cores 35 which have internal walls spaced from the manifold cores 16 to provide chambers 36 surrounding these cores and communicating with the end gate passages 32 through the passages 33, in the cores 28. These thin cores 70 35 are also constructed to provide thin fin spaces 37 at the opposite sides of and communicating with the space or chambers 36, and these fin spaces 37 also communicate with the end gate passages 32 through the passages 34 in the cores 28. 75 Interposed between the inner cores 35, is a series

of thin fin cores 38 which complete the mold structure. These cores 38 have internal walls which completely surround and are spaced from the header cores 17 to provide chambers 39, and are also formed to provide thin fin spaces 40 connecting the chambers 39 and communicating with the end and center gate through the passages 34, 23 respectively. Both sets of thin cores 35, 38 rest directly upon the upper surface of the slab core portion 14 and are locked to the base core by 10 projections 21 formed integral therewith, and all of these cores 35, 38 are moreover provided with interlocking projections 31 at the top and sides thereof, as shown in Figs. 1, 4 and 5. The passages 33 which communicate with the end gate 15 20 passages 32, are preferably disposed in alinement with the chambers 39, and as previously indicated, the passages 34 extend throughout the length of the mold and penetrate the thin cores 35, 38. The fin forming cores 35, 38 coact with each other 25 only along the top and sides, but not at the bottom, and the fin spaces 37, 40 and the header chambers 36 are bounded at the bottom only by the slab core portion 14.

When it is desired to produce a mold in accordance with the present method, the individual cores are first properly formed in a well-known manner, of the usual core sand and of the various shapes above described, and slab core portions 14, 15 of proper length dependent upon the length of radiator section which it is desired to cast, are selected. One set of end cores 27, 28, 29 are then assembled upon the slab core portion 14 after which the corresponding group of cores 35 is assembled about the adjacent manifold core 16 having the header 35 core 17 attached thereto. The fin cores 38 may subsequently be assembled upon the base core portion 14 over the header cores 17, and the length of the radiator structure will depend upon the actual number of individual fin cores 38 which 40 are utilized. After the fin cores 38 have been applied, the opposite manifold core 16, thin cores 35, and thick end cores 29, 28, 27 may be applied to complete the mold assemblage, and the assembled cores may be finally locked in assembled 45 position by applying the locking base core portion 15, inserting the base core within a retaining box 19, and by applying the end clamps 30. During the mold assembling operation, it may be found necessary to insert chaplets around the 50 conduit cores 17 if these cores are relatively long, in order to prevent raising or shifting thereof when metal is poured into the mold, and it may also be found desirable to grind the fin cores 35, 38 to proper width in order to insure proper length 55 of the final mold. Such grinding may also be resorted to along the upper face of the slab core portion 14, and along the bottom surfaces of all cores which coact with this surface. The interlock afforded by the projections 31 of the upper 60 cores will insure perfect alinement of these cores at all times, and will also prevent undesirable escape of metal during the casting operation.

When the mold has been thus properly assembled, the casting operation can be effected without embedding the composite core mold in green sand or the like, since the coacting cores insure provision of tight metal receiving chambers and spaces. The metal may be admitted to the end and central gates and flows through the passages 70 32, 33, 34, 23 into the chambers 36, 37, 39, 40 to produce a one-piece radiator section such as shown in Figs. 8, 9 and 10. In this radiator section, the manifold chambers 36', headers 39' and fins 37', 40', are all formed en bloc, and the outer- 75

most corners of the fins 37', 40' are integrally united by metal strips 34' produced by the passages 34 in the mold. The cores can be removed from the internal chambers 16', 17' through the openings 24', 25' one of each of which may be subsequently plugged, and the others of which may be utilized as inlet and discharge openings in the final radiator. If end inlet and discharge openings are preferred, the upper core prints 24 may be omitted from the chamber cores 16 and replaced by core prints extending through the outer end walls of the manifolds 36', but this method of casting insures production of uniform fin thickness and spaces between the fins 37', 40'. In order to positively guard against undesirable variation in the lengths of the radiators, a structure such as shown in Fig. 11 may be utilized. In this assemblage the fin cores 38' and one of each group of end cores 35', are provided with tapered lower end projections 41 which are adapted to coact with uniformly spaced transverse grooves 42 formed in the upper part of the base core portion 14'. During assembly of this mold, the fin cores 38' can be ground to such thickness that they will exactly fit within the successive spacing notches or grooves 42 in the slab core, so that all radiator sections produced will be of precisely the same length. The radiator sections will be the same as shown in Figs. 8, 9 and 10, and the fins 40' and intervening spaces will again be uniform.

From the foregoing description, it will be apparent that the present invention provides an improved apparatus for forming and assembling molds for the production of finned radiators or the like, whereby the radiator sections may be rapidly produced without the aid of green sand molds, and without loss of time and materials due to defective castings. Each successive casting produced by the improvement should be perfect and precisely the same as the others, if ordinary care is taken in assembling the molds. The fins 37', 40' may be cast closely adjacent to each other and of minimum thickness, and the cores 35, 38 are effectively spaced apart to provide the fin spaces and locked in alinement with each other along the sides and top only, thereby simplifying the construction of these cores. The cores may moreover be ground to provide tight joints, and may be cemented or pasted wherever desirable, although such cementing may ordinarily be dispensed with.

It should be understood that it is not desired to limit the invention to the exact details of construction and to the precise method of core mold assembly herein shown and described, for various modifications within the scope of the claims may occur to persons skilled in the art.

It is claimed and desired to secure by Letters Patent:

1. A mold for casting finned objects, which comprises, a slab core having undercut recesses in the opposite sides thereof, a conduit core spaced from said slab core, and fin cores resting upon said slab core and surrounding said conduit core, said fin cores having projections on the opposite sides thereof extending within said slab core recesses and each of said fin cores having a tongue projecting from one face thereof and a groove in its opposite face interlockable with the grooves and tongues respectively of adjoining cores.

2. A mold for casting finned objects, which comprises, a slab core having parallel spaced undercut recesses therein, and a plurality of fin cores resting in stacked relation upon said slab core and having projections at the lower opposite sides thereof extending within said slab core recesses, each of said fin cores having a tongue projecting from one face and a corresponding groove in the opposite face thereof interlockable with the grooves and tongues respectively of adjoining cores.

3. A mold for casting finned objects, which comprises, a slab core comprising separable sections forming spaced parallel undercut recesses and a supporting surface forming the corresponding side of said recesses, and a series of coacting fin cores resting upon said surface and having projections confined within said recesses to prevent displacement of said fin cores away from said slab core, each of said fin cores having a tongue projecting from one face thereof and extending around the core center from one portion of said surface to another, and each of said fin cores also having a corresponding groove in the opposite face thereof, said tongues and grooves being interlockable with the corresponding grooves and tongues respectively of adjoining cores.

4. A mold for casting finned objects, which comprises, a slab core having spaced undercut recesses connected by a common supporting surface, and a plurality of coacting fin cores resting upon said surface and having projections disposed within said recesses to prevent displacement of said fin cores away from said slab core, the adjoining fin cores having a groove and an interlocking tongue respectively at their coacting faces extending from one portion of said slab core surface around the mold space to another portion of this surface adjacent to said recesses.

5. A mold for casting finned objects, which comprises, a lower slab core having spaced undercut recesses and an upper surface connecting said recesses, and a plurality of interlocking fin cores resting upon said surface and having projections coacting with said slab core recesses to maintain said fin cores in interlocked relationship and to prevent displacement of said fin cores away from said slab core.

6. A mold for casting finned objects, which comprises, a slab core comprising coacting elongated sections having parallel spaced undercut recesses connected by an upper supporting surface, and a plurality of interlocking fin cores resting upon said slab core surface and having projections at the opposite lower side portions thereof interlocking with said recesses to prevent displacement of said fin cores away from said slab core surface.

7. A mold for casting finned objects, which comprises, a slab core having spaced undercut recesses extending longitudinally thereof and a surface connecting said recesses, and a plurality of fin cores coacting with each other to provide fin spaces bounded at the bottom by said slab core surface, adjoining fin cores having interlocking grooves and tongues and all of said fin cores having projections interlocking with said slab core recesses to prevent displacement of said fin cores away from said slab core surface.
